UNITED STATES PATENT OFFICE.

ROBERT STANLEY LEWIS, OF IPSWICH, ENGLAND, ASSIGNOR OF ONE-HALF TO RAN-
SOMES & RAPIER LIMITED, OF IPSWICH, ENGLAND, A COMPANY.

HOISTING AND LUFTING MECHANISM FOR CRANES.

Application filed October 2, 1922. Serial No. 591,915.

To all whom it may concern:

Be it known that I, ROBERT STANLEY LEWIS, a subject of the King of England, and residing at Ipswich, Suffolk, in England, have invented certain new and useful Improvements in Hoisting and Luffing Mechanism for Cranes, of which the following is a specification.

This invention relates to cranes of the kind 10 in which mechanisms for hoisting the load and luffing the jib can be so coupled to a single source of power as to be driven either alone or simultaneously, a brake holding that mechanism not in use against movement.

The object of the invention is to provide a compact and light mechanism by means of which the crane can be controlled in a simple manner, as is particularly desirable when 20 the crane is of the locomotive or travelling type.

According to this invention the driven member or members normally engage a stationary brake and this brake is released automatically when the two parts of a friction clutch carried respectively by the driven and driving members are brought into engagement. Preferably the construction is such that when axial movement in one direction 25 is imparted to the driving member or to a clutch carried thereby, the two clutch members on the driving and driven members are gradually and progressively coupled together while simultaneously the driven member 30 gradually disengages its stationary braking surface. Conversely axial movement in the opposite direction gradually disengages the two halves of the clutch and simultaneously applies the brake in a gradual or progressive manner.

To this end the driving and driven members are arranged coaxially with one another and in the preferred construction the driving member is disposed centrally between 45 two driven members each of which carries a combined clutch and brake member adapted respectively to engage a clutch part carried by or rotating with the driving member and a stationary brake cone surrounding the 50 driven shaft. The two driven members are respectively geared to a hoisting barrel or winding barrel and preferably all the clutch and brake mechanism is enclosed in a suitable casing from which project only the driving pinions and the springs tending to main-

tain the driven members in engagement with their brakes.

In the accompanying drawings:—

Figure 1 is a central sectional elevation through the driving and driven members, 60 showing the hoisting and luffing barrels and their driving pinions, and

Figure 2 is a plan, on a reduced scale.

In the construction illustrated a driving member comprising a worm wheel A' keyed 65 to a sleeve A is mounted to rotate upon a fixed shaft B the ends of which are supported in suitable standards C. The worm wheel A is engaged by a worm D driven by an electric motor indicated at C' Figure 2 connect- 70 ed to the casing C² containing the driving member A, clutch members and brake members hereinafter described.

Formed within and preferably integral with the casing C² are vertical partitions C³ 75 bored to form supporting bearings for the driving member A. The vertical members C³ also support fixed cams E which are drilled so as to clear the driving sleeve A. Surrounding the cam-faces on the members 80 E are annular bearing members E' in which cam-shaped bosses F are mounted to rotate, these bosses being adapted to co-operate with the cams E and being provided with operating levers F' extending through slots C⁴ in 85 the top of the casing C².

Mounted on each end of the driving sleeve A is an externally coned friction clutch member G, capable of axial movement upon the sleeve but keyed to the sleeve so as to 90 rotate therewith. Each clutch member G is normally forced towards the worm wheel A' by means of a spring G', but by rotating the cams F by means of their operating levers F', axial movement may be imparted to the 95 clutch members owing to the co-operation between the inclined faces of the rotary cams F and fixed cams E.

Near each end of the shaft B is a driven member which can rotate and also slide in an axial direction upon the shaft. One driven member H carries a pinion H' meshing with the driving wheel of the hoisting barrel H². The other driven member J has a pinion J' meshing with the driving wheel of the derrick or luffing barrel J². The driven members are of similar construction and are normally forced towards the driving worm wheel A' by means of their respective spiral springs H³, J³. 105

The driven members each carry a combined clutch and brake member, the clutch members H^4 , J^4 being internally coned to receive and engage the driving clutches G and the brake members H^5 , J^5 being externally coned to engage fixed brake members K and K' secured to the casing C^2 .

The clutch members G , H^4 , J^4 are so arranged with relation to the fixed brake members K , K' and externally coned movable brake members H^5 , J^5 that if the clutches are engaged, the brakes are released and vice versa. In Figure 1 the derrick barrel J^2 is shown as held against rotation, the brake J^5 of the driven member J being in engagement with its fixed braking cone K' under the action of the spring J^3 and the clutch G being held out of engagement with the internally coned clutch member J^4 by means 20 of the clutch spring G' .

On the other hand, the driven member H is shown as having been moved axially away from the driving member against the action of its spring H^3 through the rotation of the 25 cam F relatively to the fixed cam E . As a result the clutch H^4 has been engaged by the clutch G and the brake H^5 has been moved out of engagement with the fixed brake cone K so that the hoisting barrel H^2 will be rotated.

The pinions H' , J' are in constant mesh with the wheels on their respective barrels and when the cam levers F' are moved, either to engage or disconnect the clutch 35 members H^4 , J^4 , these clutches will operate in a gradual or progressive manner, the respective brake H^5 , J^5 being applied or released in proportion to the extent of engagement between the two parts of the corresponding clutch.

In the drawings certain features forming no part of the invention are omitted to prevent confusion and the hoisting and derrick barrels are shown only in outline.

45 It is to be understood that the constructional details may vary considerably without departing from this invention, and that although a barrel has been shown for varying the inclination of the derrick if desired 50 some other known means may be employed as for example a screwthreaded shaft controlled by the clutch and brake mechanism already described.

What I claim as my invention and desire 55 to secure by Letters Patent is:—

1. In hoisting and luffing mechanism for cranes the combination of a driving member, driven members coaxial therewith on either side thereof, a luffing mechanism 60 geared to one of the driven members, a hoisting mechanism geared to the other driven member, a clutch member on each driven member, corresponding clutch members on the driving member, a brake member on each driven member, a stationary

brake surface for each brake, means tending normally to apply said brakes and means for imparting axial movement to the driving clutch members so as to couple the driving and driven members and simultaneously 70 release the corresponding brake.

2. In hoisting and luffing mechanism for cranes the combination of a driving member, driven members coaxial therewith on either side thereof, a luffing mechanism 75 geared to one of the driven members, a hoisting mechanism geared to the other driven member, a stationary brake surface for each driven member, a clutch member for each driven member on the driving member, a combined brake and clutch member on each driven member, means tending normally to maintain said combined members out of engagement with their respective driving clutch and in engagement with their stationary brake surfaces, and means for imparting axial movement to the driving clutch members to couple the driving and driven members and simultaneously disengage the corresponding brake members.

3. In hoisting and luffing mechanism for cranes the combination of a driving member, driven members coaxial therewith on either side thereof, a luffing mechanism geared to one of the driven members, a hoisting mechanism 80 geared to the other driven member, a stationary brake surface for each driven member, a conical clutch member for each driven member mounted to slide upon the driving member, a correspondingly coned clutch member on each driven member, a brake surface on each driven clutch member, means tending normally to maintain said brake surfaces in contact with their respective stationary brake surfaces, and independently operated means for sliding the driving clutches into engagement with their corresponding driven clutch members whereby these clutches are progressively coupled 100 and the corresponding brake members are simultaneously released, axial movement in the opposite direction disengaging the clutch members and simultaneously applying the brake.

4. In hoisting and luffing mechanism for cranes the combination of a driving member, an axially movable driven member mounted to rotate on either side thereof and coaxial therewith, hoisting and luffing mechanism respectively geared to said driven members, a combined clutch and brake member carried by each driven member, a stationary brake cone normally engaged by the brake portion of each driven member, friction clutches for each driven member mounted to slide upon the driving member and independently operated cams for sliding the driving clutches into engagement with their corresponding driven clutch members, each clutch being thus progressively cou- 115 120 125 130 135

- pled and simultaneously the corresponding driven member being moved in an axial direction so that its brake members are caused to disengage in a correspondingly progressive manner, axial movement in the opposite direction disengaging the two parts of the clutch and simultaneously applying the corresponding brake in a progressive manner.
- 10 5. In hoisting and luffing mechanism for cranes the combination of a driving member, an axially movable driven member mounted to rotate on either side thereof and coaxial therewith, hoisting and luffing mechanism respectively geared to said driven members, a coned friction clutch member and a braking cone forming part of each driven member, a stationary brake cone for each of said brake cones, springs tending normally to 20 maintain said brake members in engagement with their respective stationary brake cones, a friction clutch for each driven member mounted to rotate with the driving member and adapted to slide in an axial direction relatively to the driven member, 25 cams rotatably mounted on the driven member, and independently operated means for rotating said cams to impart axial movement to the driving clutches and thereby to the driven members in opposition to their 30 controlling springs, whereby the two parts of the clutch are caused to engage and simultaneously the corresponding brake members are disengaged in a gradual manner, rotation of the cam in the opposite direction permitting the controlling spring to disconnect the clutch members and simultaneously apply the brake in a gradual and progressive manner.
- 35 In testimony whereof I have signed my name to this specification.

ROBERT STANLEY LEWIS.
